UNITED STATES PATENT OFFICE.

LOUIS COATALEN, OF WOLVERHAMPTON, ENGLAND, ASSIGNOR OF ONE-HALF TO
SUNBEAM MOTOR CAR COMPANY LIMITED, OF WOLVERHAMPTON, ENGLAND.
INTERNAL-COMBUSTION ENGINE.

1,248,266.

Specification of Letters Patent. Patented Nov. 27, 1917.

Application filed December 4, 1916. Serial No. 135,048.

To all whom it may concern:

Be it known that I, LOUIS COATALEN, a subject of the King of Great Britain, and resident of Wolverhampton, in the county 5 of Stafford, England, have invented certain new and useful Improvements in Internal-Combustion Engines, of which the following is a specification.

This invention relates to internal combustion engines, and has for its object to provide a simple construction which is light, and in which the number of large castings or parts is reduced to a minimum.

According to this invention, the water jacket of aluminium alloy is formed integral with part of the crank chamber and inside this is fitted a liner of cast iron, steel, or other suitable material, and to the water jacket is attached a cylinder head casting 15 of aluminium alloy which carries the cam shaft or cam shafts, valves, valve seatings, and the gas passages. Preferably the liner is flanged at its upper end and the flanges are gripped between suitable surfaces on 20 the head and jacket.

The accompanying drawing is a central vertical section showing how the invention may be carried into effect.

As will be seen, the upper part A of the 30 crank chamber, which is constructed of cast aluminium alloy, is extended up to form a complete water jacket the walls of which are shown at B these being joined together at B². The casting constituted by the parts 35 A B may include any suitable number of cylinders in line, and to it is bolted a separate cylinder head casting C also of aluminium alloy, which is provided with a water jacket C². Into the jacket portion B fits, 40 for each cylinder, a liner D of cast iron, steel or other suitable metal and this is flanged at D² the flange being gripped between the head and the upper edge B² of the jacket. Any suitable packing material 45 or a gasket E may be used and the water jacket of the head may connect with the cylinder water jacket in any well known manner.

The valves F seat upon detachable seating rings G which screw into the head casting, though they may be fixed in other ways. These seating rings may be of steel, bronze or other suitable material and it will be seen that the gas passages H are also formed 55 in the head casting. Loose bushes J are

fixed in the casting and serve as guides for the valve stems, and suitable bearings are provided for the cam shafts K. The cams K² actuate the valves through rockers L which are pivoted either to the wall C³ of 60 the head casting or to the detachable cover plates M thereon. Preferably the walls C³ extend up to the point C⁴ so as to inclose the cam shafts on the outer side and serve to catch oil. A similar wall may extend 65 up on the inside, but preferably there is employed a separate cover plate N with its walls N² extending down and serving to inclose the cam shafts on the inner side. The aperture N³ serves for access to the spark- 70 plugs which are located centrally between the two valves.

By this means the engine construction is greatly simplified as there are only two main castings B and C of any size, the crank 75 chamber and cylinder water jacket forming one, and the head carrying practically all the valve mechanism constituting the other. Previously where there has been used one casting of aluminium alloy combining the 80 main or cylinder water jacket and the upper part of the crank chamber, and a detachable head casting, the latter has been made of cast iron or similar material, with the result that the joint between the head and 85 the upper surface of the cylinder casting was liable to become very hot and moreover the two castings expanded differently, having different co-efficients of expansion. By the present invention the expansion of 90 the two parts is similar and the engine is much lighter. As the flange D² on the liner is gripped between two cooled aluminium 95 surfaces, it is prevented from becoming very hot, owing to the high conductivity of aluminium.

What I claim as my invention and desire to secure by Letters Patent, is:—

1. In an internal combustion engine, the combination of a complete water jacket of 100 aluminium alloy, a crank chamber part integral therewith, a separate liner in said jacket insertible therein from the top thereof, a separate cylinder head casting of 105 aluminium alloy, cam shafts carried by said head, valves in said head, and separate valve seatings insertible into said head from below and fixed thereto, substantially as set forth.
2. In an internal combustion engine, the 110

combination of a complete water jacket of aluminium alloy, a crank chamber part integral therewith, a separate liner in said jacket, a cylinder head casting of aluminium alloy, cam shafts carried by said head, valves in said head, separate valve seatings fixed to said head, walls extending above said cam shafts, cover plates in said walls, rockers pivoted to said cover plates, and a 10 cover plate between said cam shafts with a

central aperture therein, substantially as set forth.

In testimony whereof I have signed my name to this specification in the presence of two subscribing witnesses.

LOUIS COATALEN.
